UNITED STATES PATENT OFFICE.

WILLIAM H. DE BUSK, OF CHICAGO, ILLINOIS, ASSIGNOR TO THE P. & M. COMPANY,
OF CHICAGO, ILLINOIS, A CORPORATION OF ILLINOIS.

RAIL ANCHOR.

Application filed June 23, 1924. Serial No. 721,861.

To all whom it may concern:

Be it known that I, WILLIAM H. DE BUSK, a citizen of the United States, residing at Chicago, in the county of Cook and State of Illinois, have invented certain new and useful Improvements in Rail Anchors, of which the following is a specification.

My invention relates to rail anchors and it has for its object the provision of a new and improved form and arrangement of parts in a one-piece rail anchor whereby there shall be an effective grip of the device upon the flange of a rail and there shall be provided a proper bearing upon a cross tie by the use of a minimum amount of metal so that the anchor can be produced upon a commercial basis at a minimum cost.

It is another object of my invention to improve devices of this type in sundry details hereinafter pointed out. That which I believe to be new and desire to cover by this application is set forth in the claims.

In the drawings,

Fig. 1 is a top plan view of one form of my improved rail anchor applied to a rail, partly broken away, showing the bearing of the anchor upon the cross tie.

Fig. 2 is a face view of the blank from which the anchor of Fig. 1 is produced.

Fig. 3 is a vertical cross section taken on line 3—3 of Fig. 1.

Fig. 4 is a top plan view showing a modified form of anchor applied to a rail.

Fig. 5 is a face view of the blank from which the anchor of Fig. 4 is produced.

Fig. 6 is a cross sectional view of a rail, partly broken away, with the anchor of Fig. 4 in its initial position as it is being applied to the rail.

Fig. 7 is a top plan view of another modified form of anchor.

Fig. 8 is a face view of the blank from which the anchor of Fig. 7 is produced.

Fig. 9 is a top plan view of still another modified form of anchor.

Fig. 10 is a face view of a blank from which the anchor of Fig. 9 is produced.

Figs. 11, 12, 13 and 14 are top plan views showing four additional modified forms of anchor applied to a rail.

Referring to Figs. 1 to 3, 20 indicates a rail supported by a cross tie 21 as is best

shown in Fig. 2. The improved anchor as applied to the rail in Fig. 1 is formed as a stamping from a heavy piece of metal, comprising a body 22, a jaw 23 at one end, and a jaw 24 at the opposite end. The jaw 23 has integrally formed therewith a vertical shoulder 25 which in the applied position of the anchor is adapted to engage the side face of the flange, at one side of the rail, as shown in Fig. 1. At the opposite end, the anchor comprises also a tongue 26 providing a vertical shoulder independently of the adjacent jaw 24. The jaw 23 and the tongue 26 are to be bent in opposite directions out of the plane of the body of the anchor, as is shown in Fig. 1, so as to insure engagement between such parts and the side faces of the flange of the rail at points substantially opposite each other transversely of the rail, the dimensions of the parts and their relative positioning being such that when such parts are in engagement with the faces of the flange the anchor is incapable of swinging to any appreciable extent with respect to the rail. The jaw 24 is made of such length and of such dimensions that it is comparatively very much more resilient than the remaining parts of the anchor so that in the application of the device to a rail the jaw 24 can readily be forced laterally with respect to the rail so as to cause the jaw to snap past the edge of the flange and assume the desired position in contact with the upper face of the flange, as is shown in Fig. 3. The jaw 24 is to be of such strength as to hold the anchor normally in operative position on the rail, it being unnecessary to give the jaw 24 any greater amount of strength than for the accomplishment of this purpose, inasmuch as there is in use no tendency of the anchor to twist or cant against the action of the jaw 24.

As is clearly shown in Fig. 1, the anchor has a bearing at 27 against the cross tie 21, such bearing being provided without the extension of the body 22 to any extent beyond the normal length required independently of such bearing. The bearing at 27 is also provided without the necessity for any offsetting of any part of the anchor with respect to the body 22. This effect is obtained by reason of the fact that the shoulder 25 and

the tongue 26 bear upon the side faces of the rail at points outside of the plane of the body of the anchor. As will be readily understood, when the rail 20 tends to creep in the direction indicated by the arrow in Fig. 1, the tongue 26 and the shoulder 25 have a shackle hold upon the side faces of the flange of the rail, such hold being tightened as the tendency of the rail to creep increases. At the same time, there is a second shackle hold upon the top and bottom faces of the flange between the bottom face 28 of the jaw 23 and the top face of the body at 29. By the provision of this shackle hold feature of the anchor, the device is enabled to grip the rail very effectively so as to prevent longitudinal movement of the rail as is well understood in the art.

In Figs. 4, 5 and 6, a construction is illustrated similar to that shown in Figs. 1, 2 and 3, but differing therefrom in certain respects, as will be set forth. The parts in Figs. 4, 5 and 6 corresponding to the parts of the construction above described, are indicated by the same reference characters.

The principal difference between the construction shown in Figs. 4, 5, and 6 as compared with the construction shown in Figs. 1, 2 and 3 resides in the fact that a shoulder 30 is provided upon the body 22 adjacent to the jaw 24 without the use of a separately formed tongue such as the tongue 26 of the construction first described. This construction is rendered feasible by making the jaw 23 of very considerably greater length than the jaw 23 of the first construction described, so that the shoulder 25 will engage the edge of the rail base at some little distance from the face of the body 22 and at a point substantially opposite the point of engagement of the shoulder 30 transversely of the rail. That is to say, by making the jaw 23 longer the necessity for displacing the shoulder 30 from the plane of the body is obviated.

As is best shown in Fig. 5, the upper end portion of the shoulder 30 is diagonally disposed at 31 so as to act as a cam surface for assisting in the application of the anchor to the rail, as is indicated in Fig. 6.

The construction illustrated in Figs. 7 and 8 is quite similar to that last described, as is seen by a comparison of Fig. 8 with Fig. 5. The device of Figs. 7 and 8, however, is provided with a short jaw 23 in lieu of the long jaw 23 as shown in Fig. 4, while at the same time the shoulder 30 is provided without the use of a tongue corresponding to the tongue 26 of Fig. 1. This result is attained by the provision of a bend or offset in the body of the anchor between the shoulder 25 and the shoulder 30 so as to bring the bearing points between such shoulders and the side faces of the flange transversely opposite each other as is shown in Fig. 7,

the offset or bend in the body also providing the bearing upon the cross tie 21 at the point 32 between the shoulders 25 and 30.

In Figs. 9 and 10, a shoulder 33 is provided rising directly from the body 22 rather than depending from the jaw 23 as in the formerly described constructions. In this construction, the points at which the shoulders 30 and 33 engage the side faces of the flange are brought opposite to each other transversely of the rail by the expedient of turning the edges of the shoulders very slightly, as is clearly shown in Fig. 9, by the application of pressure thereon.

In the construction shown in Fig. 11 the edges of the shoulders are rounded in the same manner as that above described in connection with the structure of Fig. 9. In this construction, however, reliance is not placed entirely upon the diagonal position of the anchor for the limited bearing of the anchor against the cross tie 21, but on the contrary the end portion 34 is offset with respect to the body 22.

In the construction illustrated in Fig. 12, the edges of the shoulders 30 and 33 are not rounded as are the shoulders 33 and 30 of the anchor of Fig. 11, such rounding being unnecessary in view of the fact that the body of the anchor is permitted to swing past the directly transverse position by reason of the provision of a considerably greater offset 35 at the end of the anchor. That is to say, the offset 35 is displaced considerably farther from the plane of the body of the anchor than is the offset 34. In this construction the anchor tightens against the side faces of the rail by reason of swinging past the transverse position rather than by a tightening effect before the body passes such transverse position. The construction is such, however, that the anchor is to be applied in substantially its operative tightened position by a displacement of the jaw 24 laterally with respect to the rail, as distinguished from the constructions of the prior art in which the shoulders are tightened upon the side faces of the flange by reason of the swinging motion of the anchor with respect to the rail.

In the construction of Fig. 13, the bearings of the shoulders adjacent to the jaws 23 and 24, respectively, against the side faces of the flange of the rail are brought into transversely opposite positions with respect to each other by reason of the fact that such shoulders 36 and 37 are cut diagonally with respect to the body 22 so as to insure the contact of the shoulder in each case adjacent to the proper face of the body 22, all as is indicated clearly in Fig. 13.

In the construction shown in Fig. 14, the directly transverse positioning of the bearing portions of the shoulders against the side faces of the flange is attained by the

provision of offsets adjacent to such shoulders, the offsetting having the effect of changing the direction of the face of the shoulder so as to provide the desired effect.

5 In Fig. 14 the shoulders are indicated by reference characters 38 and 39, respectively.

So far as I am aware, I am the first in the art to provide an anchor of this type comprising two shoulders positioned at a 10 distance from each other substantially equal to the width of the flange of the rail whereby the anchor is capable of being applied to the rail with a shoulder on each side of the flange in such manner that the body of the 15 anchor is not capable of swinging horizontally with respect to the rail, such device being provided with a comparatively very flexible jaw which is adapted to be displaced laterally with respect to the rail so 20 as to snap into position in engagement with the upper face of the flange.

While I prefer to employ one of the constructions as set forth in the drawings, it will be understood that I do not desire to 25 limit myself to the precise constructions so illustrated, inasmuch as it is evident that changes might be made in the constructions without departing from the spirit of my invention.

30 I claim:

1. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid for applying pressure upon the upper face of the flange at one side, and the other jaw being comparatively much more resilient so as to be capable of being displaced readily for snapping into engagement with the upper face of the flange at the opposite side.

2. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid and being bent from the plane of the body of the anchor in the direction toward the cross tie so as to bear upon the upper face of the flange at one side of the rail, and the other jaw being displaced from the plane of the body of the anchor in the direction away from the cross tie and being comparatively much more re-

silient so as to be capable of being displaced readily for snapping into engagement with the upper face of the flange adjacent thereto.

3. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid for applying pressure upon the upper face of the flange at one side, and the other jaw being adapted to be flexed independently of the adjacent shoulder and being comparatively much more resilient than the first mentioned jaw so as to be capable of being displaced readily for snapping into engagement with the upper face of the flange at the opposite side, said shoulders being so positioned with respect to the body that when their bearing points on the side faces of the flange are substantially opposite each other transversely of the rail the body stands at a slight angle with respect to the directly transverse position.

4. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid and being bent from the plane of the body of the anchor in the direction toward the cross tie so as to bear upon the upper face of the flange at one side of the rail, and the other jaw being displaced from the plane of the body of the anchor in the direction away from the cross tie and being comparatively much more resilient than the first mentioned jaw and adapted to be flexed independently of the adjacent shoulder so as to be capable of being displaced readily for snapping into engagement with the upper face of the flange adjacent thereto, said shoulders being so positioned with respect to the body that when their bearing points on the side faces of the flange are substantially opposite each other transversely of the rail the body stands at a slight angle with respect to the directly transverse position.

5. A rail anchor comprising a body adapted to extend across beneath a rail, a jaw on each end of the anchor adapted to engage the upper face of the base flange of the rail, shoulders on said anchor in spaced relation at a distance from each

other substantially equal to the width of the flange of the rail adapted to engage the side faces of the flange and prevent swinging movement of the body with respect to the rail, one of said jaws being substantially rigid and being bent from the plane of the body of the anchor in the direction toward the cross tie so as to bear upon the upper face of the flange at one side of the rail, and the other jaw being displaced from the plane of the body of the anchor in the direction away from the cross tie and being comparatively much more resilient so as to be capable of being displaced readily for snapping into engagement with the upper face of the flange adjacent thereto, one of said shoulders being displaced from the plane of the body in the direction toward which the adjacent jaw is displaced.

6. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid and being bent from the plane of the body of the anchor in the direction toward the cross tie so as to apply pressure upon the upper face of the flange at that side of the rail, and the other jaw being displaced from the plane of the body of the anchor in the direction away from the cross tie and being comparatively much more resilient so as to be capable of being displaced readily for snapping into engagement with the upper face of the flange adjacent thereto, both of said shoulders being displaced from the plane of the body in the direction toward which the adjacent jaw is displaced.

7. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid for applying pressure upon the upper face of the flange at one side, and the other jaw being comparatively much more resilient so as to be capable of being displaced readily for snapping into engagement with the upper face of the flange at the opposite side, said shoulders being displaced in opposite directions from the plane of the body.

8. A rail anchor comprising a body adapted to extend across beneath a rail, a jaw on

each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid for applying pressure upon the upper face of the flange at one side, and the other jaw being comparatively much more resilient so as to be capable of being displaced readily for snapping into engagement with the upper face of the flange at the opposite side, the shoulder at the end of the anchor adjacent to the more resilient jaw being formed independently of said jaw. 70 75 80

9. A rail anchor comprising a body adapted to extend across beneath a rail, a jaw on each end of the anchor adapted to engage the upper face of the base flange of the rail, shoulders on said anchor in spaced relation at a distance from each other substantially equal to the width of the flange of the rail adapted to engage the side faces of the flange and prevent swinging movement of the body with respect to the rail, one of said jaws being substantially rigid for applying pressure upon the upper face of the flange at one side, and the other jaw being comparatively much more resilient so as to be capable of being displaced readily for snapping into engagement with the upper face of the flange at the opposite side, the shoulder at the end of the anchor adjacent to the more rigid jaw being provided as a vertically disposed face on the jaw. 85 90 95 100

10. A rail anchor comprising a body adapted to abut against a cross tie and extend across beneath a rail at an angle to the tie, and jaws on opposite ends of the body adapted to engage the upper face of the base flange of the rail at opposite sides of the rail, said jaws being disposed in such position and at such distance from each other that it is necessary to displace one of the jaws transversely of the rail when applying the anchor in operative position on the rail, one of said jaws being bent out of the plane of the body of the anchor in the direction away from the cross tie and being of comparatively much greater resiliency than that of the other jaw whereby substantially all of the distortion of the parts for the application of the anchor to a rail occurs in the jaw so bent away from the cross tie. 105 110 115 120

11. A rail anchor comprising a body adapted to abut against a cross tie and extend across beneath a rail at an angle to the tie, and jaws on opposite ends of the body adapted to engage the upper face of the base flange of the rail at opposite sides of the rail, said jaws being disposed in such position and at such distance from each other 130

that it is necessary to displace one of the jaws transversely of the rail when applying the anchor in operative position on the rail, a bearing for the anchor upon the cross tie being provided at one end of the body, and the jaw at that end of the body being bent out of the plane of the body in the direction

away from the cross tie and being of comparatively much greater resiliency than that of the other jaw whereby substantially all of the distortion of the parts for the application of the anchor to a rail occurs in the jaw so bent away from the cross tie. 10

WILLIAM H. DE BUSK.
